UNITED STATES PATENT OFFICE.

JOSEPH L. FIRM, OF BERWYN, ILLINOIS, ASSIGNOR TO THE GOSS PRINTING PRESS COMPANY, OF CHICAGO, ILLINOIS, A CORPORATION OF ILLINOIS.

PRINTING-PRESS.

1,025,258.

Specification of Letters Patent.

Patented May 7, 1912.

Application filed January 3, 1911. Serial No. 600,450.

To all whom it may concern:

Be it known that I, JOSEPH L. FIRM, a citizen of the United States, and a resident of the city of Berwyn, county of Cook, and State of Illinois, have invented certain new and useful Improvements in Printing-Presses, of which the following is a specification.

This invention relates to improvements in printing presses and more specifically to the multicolor printing type.

The object of my invention is the production of a machine by means of which a plurality of colors may be offset or transferred at one operation.

A further object is the production of a printing mechanism as mentioned which will be of durable construction, and of great efficiency in operation.

20 Other objects will appear hereinafter.

With these objects in view my invention consists in the combinations and arrangements of parts hereinafter described and claimed.

25 My invention will be best understood by reference to the accompanying drawings forming a part of this specification, and in which—

Figure 1 is a side elevation of a printing press embodying the invention, Fig. 2 is a plan view of a cam member included in the construction, and Fig. 3 is a diagrammatic view of the device in longitudinal section.

The preferred form of my invention as 35 illustrated in the drawings comprises a supporting body or frame 1 in which is rotatably mounted a transversely extending shaft 2. Fixed to the shaft 2 is a form cylinder 3 upon which is arranged a plurality 40 of forms or plates, four being shown equally spaced thereon, the same being designated as 4, 4', 4" and 4'''.

Arranged about the form cylinder 3 are preferably equally spaced inking devices or 45 mechanisms 5, 5', 5" and 5''', the same being of any well-known or preferred construction. Said inking mechanisms are adapted to contact and apply ink to the plates or forms carried by said cylinder, the 50 same being however, so mounted as to be adapted to be moved into and out of engagement with said cylinder so that each will contact with a portion of the periphery of the form cylinder, that is, with one of the 55 plates or forms carried thereby different

from that engaged by the others, the inking mechanism 5 being arranged for engagement with the plate 4; the mechanism 5' with the plate 4'; the mechanism 5" with the plate 4", and the mechanism 5''' with the plate 4'''.. With this arrangement then, different colors or inks being contained in the different inking mechanisms, different colors will obviously be correspondingly applied to the different forms or plates upon the cylinder 60 3; so that if yellow ink is contained in the mechanism 5, yellow ink and only this color of ink will be applied to the plate 4, and if blue ink is contained in the mechanism 5', the blue ink and only blue ink will be applied to the plate 4', and so on.

The mechanism for effecting the movement of the inking mechanisms into and out of contact with the form cylinder upon rotation of the latter, is substantially the same 75 as that employed in my Letters Patent #677,735 granted July 2, 1901, see particularly Fig. 2. Briefly, however, the mechanism whereby such movement is secured is thus:—The different inking mechanisms 5, 80 5', 5" and 5''' are mounted in frames 6, 6', 6" and 6''', respectively, which frames are slidably mounted upon the body frame 1 for movement in a direction radial with respect to the form cylinder. Intermittent outward 85 movement of said mechanisms is effected by means of bell crank levers 7 which are fulcrumed at 7' in the frame 1; the outer ends of said levers being provided with rollers 8 which engage against the undersides of said 90 inking - mechanism - carrier - frames so that when the inner ends of said levers are rocked outwardly said frames will be correspondingly moved outwardly by the rollers 8 engaging the same, and when said inner ends 95 of said bell crank levers are moved inwardly, said carrier-frames will be permitted to be moved correspondingly inwardly to effect the engagement of the inking mechanisms with the form cylinder. The inner 100 extremities of the inner arms or ends of the bell crank levers 7 co-operating with each of the carrier-frames are pivotally connected, rollers 9 being provided at the junctures of said lever extremities. The rollers 105 9 engage against the peripheries of cams 10 which are fixed upon the extremities of the shaft 2, the cams 10 at each extremity of said shaft being preferably formed integral as clearly shown in Fig. 2. Each of the 110

cams 10 is so formed that during each rotation thereof, the roller 9 co-acting therewith will during the greater part of the rotation be held at its outer terminal of 5 movement, the same being however, permitted to move inwardly during a small portion of such rotation, as will be obvious by reference to Fig. 1. The arrangement is such, that when the roller 9 is at its outer 10 terminal of movement the inking mechanism coöperating therewith will be held in inoperative position, and when said roller is at its inner terminal of movement said mechanism will be permitted to be moved inwardly 15 by the tension spring 11 coöperating therewith to operative position; the cams 10 being so arranged and designed that each of the inking mechanisms will remain in operative position for a period of time only 20 sufficient to effect the application of ink to the plate or form coöperating therewith, as above described.

Rotatably mounted in the frame 1 tangentially with the cylinder 3, is an offset cylinder 12, the latter being preferably provided with a rubber coat 13 which facilitates the ready removal or offsetting of the ink from said cylinder when the device is in operation. Said cylinder 12 remains constantly 25 in contact with the periphery of the cylinder 3, said cylinders 3 and 12 being so proportioned that the periphery of the former is to the periphery of the latter directly as the number of inking mechanisms coöperating 30 with said form cylinder; so that in the construction illustrated, wherein four inking mechanisms are employed, the periphery of the cylinder 12 will be one-fourth that of the cylinder 3 and so that, with each complete rotation of the cylinder 3, the cylinder 12 will be moved through four rotations. With this construction, then, it will be observed that each of the forms or plates carried by the cylinder 3 will contact the periphery of the cylinder 12 at exactly the 45 same position, the ink carried by said forms or plates being applied to said offset cylinder one directly upon the other. Rotatably mounted in the frame 1 adjacent the opposite side of the cylinder 12 is the impression cylinder 14 which is adapted once every fourth revolution of said offset cylinder to be brought into contact with the latter. Arranged below the impression cylinder 14 is 50 an ordinary form cylinder 15 and arranged for coöperation therewith an impression cylinder 16, the cylinder 14 being adapted to apply a single color ink to the opposite side of the web to that upon which the color 55 inks are applied. The cylinders 14 and 16 carry gears 17 and 18 respectively, which mesh with each other thereby establishing connection between the former. The extremities of the shaft of the cylinder 14 are 60 journaled at the vertices of bell crank levers

19 which are fulcrumed at 20 upon the opposite extremities of the shaft of the cylinder 16. The opposite extremities of the levers 19 are provided with rollers 21 which engage cam grooves 22 formed in the outer surfaces of the outermost of the cam members 10. The arrangement is such, as will be observed, that said cam grooves will serve to maintain the cylinder 14 out of contact with the cylinder 12 during three rotations of the latter, the same being forced into contact therewith only every fourth rotation or once every complete rotation of the cylinder 3, as above mentioned. Arranged in the periphery of the cylinder 14 are gripping devices 23 which are adapted to engage the extremity of the web cut 24 fed thereto and carry the same substantially half way around said cylinder or until said extremity is engaged by gripping devices 23' arranged in the periphery of the cylinder 16, said gripping devices 23' being adapted to carry said extremity to engagement with the periphery of the form cylinder 15. The gripping devices 23 and 23' may be of any well known type, gripping devices of the construction shown and described in my Letters Patent #366,388 granted July 12th, 1887, being preferably employed.

Mounted at one extremity of the frame 1 is the web roll 25, the web in unwinding therefrom passing over guide rollers 26 and thence between superimposed cutting cylinders 27 and 28, said cylinders 27 and 28 being operatively connected by meshing gears 29 and 30 carried respectively thereby. The gear 29 is operatively connected through a train of gears 31 with the gear 17 carried by the impression cylinder 14. As above mentioned, the cylinder 14, when the machine is in operation, is oscillated slightly, such oscillation, being so limited however, that when said cylinder is moved toward the offset cylinder 12, the gear 17 carried thereby will not be moved out of mesh with the adjacent gear of the train 31. From the cylinders 27 and 28, the cuts of the web after the latter has been severed by the cutting devices carried by the cylinders 27 and 28 are guided through rollers 32 for engagement by the gripping devices 23 carried by the impression cylinder 14, whence the same are carried and acted upon in the manner above described. Strippers 33 are preferably employed at the rollers 32 adjacent the cylinder 28, in order to effect the stripping of the web from said cylinder when the same is rotated. The cutting devices carried by the cylinders 27 and 28 are of the ordinary design, that shown and described in my Letters Patent #671,993 granted April 16, 1901, being adapted to be employed if desired. As illustrated in the drawings, the cutting device comprises essentially the serrated blade 34 which is carried by the 133

cylinder 28 and the longitudinally extending recess 35 which is formed in the periphery of the cylinder 27, said blade and recess being so positioned as to be adapted 5 to register with each other when said cylinders are rotated.

Cylinders 14, 27 and 28 are driven intermittently and the speed at which they are driven and the gearing connecting them is 10 such that a sheet of proper length will be delivered to cylinders 14 and 16 at the proper time as will be readily understood by those skilled in the art. Any suitable means may be employed for this purpose 15 and no claim is made herein to any specific means for cutting and feeding the paper sheets to cylinders 14 and 16.

With a construction then as above described, it will be seen that the various colors of inks will be first applied to the plates carried by the cylinder 3, the same being transferred from said plates to the periphery of the offset cylinder 12, one coat directly upon the other. After the four coats 20 have been applied to said cylinder 12, the cylinder 14 carrying the web thereon will be rocked into contact with said offset cylinder, whereupon the four coats of ink carried by the latter will be transferred or off- 25 set at one operation to the adjacent surface 30 of the web carried by said impression cylinder. In order to facilitate the ready removal or off-setting of the ink from the periphery of the offset cylinder, a water applying mechanism 41 is preferably arranged 35 for engagement with said offset cylinder, said water applying mechanism being so arranged and connected that a coat of water will be applied to the periphery of 40 said offset cylinder once every fourth rotation thereof or during the interim between the removal of ink from said cylinder to the web and the application of a new coat of ink thereto. When lithograph ink is em- 45 ployed, care should be taken that the coat of water is very light for otherwise it might interfere with the adherence of the ink in the first instance. Any suitable mechanism may be provided for operating water applying 50 mechanism 41, no claim being made herein to any specific construction for this purpose. The construction shown for accom- 55 plishing this purpose comprising a reciprocating rod 42 carrying a cam roller 43 operating in slot 22, the other end of rod 42 being connected with one arm of a bell crank lever 44, the other arm of said bell crank being connected by means of a link 45 with mechanism 41 so as to operate said 60 mechanism at the proper time. The im- 65 pression cylinder 14 and the various cylinders and rollers operatively connected therewith will be intermittently driven, that is, the same will be operated only when said impression cylinder 14 is rocked into

contact with the cylinder 12, the same remaining inert between the successive intervals of such actuation.

By the construction as set forth it will be seen that in operation, the primary colors will be first applied by the form cylinder to the offset cylinder and that the secondary colors will be applied thereover; so that, when all of the colors are offset from the offset cylinder onto the sheet, the secondary colors will be underneath and the primary colors thereover or on top. It will be observed that the order of removing the colors from the form cylinder is a complete reversal of the order of removing the same 75 now universally in vogue.

The construction as set forth is durable and economical, and the same is of high efficiency in operation.

While I have illustrated and described 85 the preferred construction for carrying my invention into effect this is capable of variation or modification without departing from the spirit of the invention. I, therefore, desire to avail myself of such variations and modifications as come within the scope of the appended claims.

Having described my invention what I claim as new and desire to secure by Letters Patent is:—

1. In a printing press, the combination of 95 a form cylinder; inking mechanism arranged for said form cylinder; an offset cylinder arranged to contact with said cylinder; and an impression cylinder and a water applying mechanism coöperating with said offset cylinder, substantially as described.

2. In a printing press, the combination of 105 a form cylinder; inking mechanisms ar- 100 ranged for coöperation with said cylinder; means adapted upon rotation of said cylinder to effect the movement of each of said inking mechanism into and out of contact with a portion of the periphery of said cylinder different from that engaged by the other inking mechanisms; an offset cylinder 110 of less diameter than said form cylinder and arranged to contact the latter; and an impression cylinder and a water applying 115 mechanism coöperating with said offset cylinder, substantially as described.

3. In a printing press, the combination of 120 a form cylinder; inking mechanisms ar- 125 ranged for coöperation with said cylinder; means adapted upon rotation of said cylinder to effect the movement of each of said inking mechanisms into and out of contact with a portion of the periphery of said cylinder different from that engaged by the other inking mechanisms; an offset cylinder adapted to contact with said form cylinder, the periphery of said form cylinder being to the periphery of said offset cylinder directly as the number of inking mechanisms co- 130

- operating with said form cylinder; and an impression cylinder and a water applying mechanism coöperating with said offset cylinder, substantially as described.
- 5 4. In a printing press, the combination of a form cylinder; inking mechanisms arranged for coöperation with said cylinder; means adapted upon rotation of said cylinder to effect the movement of each of said inking mechanisms into and out of contact with a portion of the periphery of said cylinder different from that engaged by the other inking mechanisms; an offset cylinder adapted to contact with said form cylinder, the periphery of said form cylinder being to the periphery of said offset cylinder directly as the number of inking mechanisms coöperating with said form cylinder; and
- 10 an impression cylinder and a water applying mechanism coöperating with said offset cylinder, the duration of the intervals of non-contact being to the duration of the intervals of contact of said impression cylinder and said water applying mechanism with said offset cylinder directly as the periphery of said form cylinder is to the periphery of said offset cylinder, substantially as described.
- 15

In testimony wherof I have signed my name to this specification in the presence of two subscribing witnesses.
